COMBINATION ANTENNA AND LOAD
SUPPLY SYSTEM

Norman Eustace Davis, Chelmsford, and Roland Champion Quick, Shenfield, England, assignors to Radio Corporation of America, a corporation of Delaware

Application November 22, 1932, Serial No. 643,862
In Great Britain December 19, 1931

5 Claims. (Cl. 250—33)

This invention relates to aerial systems and electrical power systems for use in connection therewith.

More particularly the invention relates to arrangements wherein it is required to supply electrical power (e. g. direct current or alternating current at the usual power supply mains frequencies) to load devices which are so positioned that said devices or the power leads thereto are relatively close to an aerial system or systems required to have directional qualities. A common example of such an arrangement arises in connection with aerial systems employed at aerodromes since normally it is necessary to provide an illumination system e. g. a signalling light system for navigation purposes, at the head or heads of the mast or masts carrying the aerial system.

In practice it is not advisable or at any rate not economical to run lighting cables or to erect auxiliary metal towers to carry cables and lights adjacent to such aerials, the difficulty being that unless special precautions, involving as a rule considerable expense be taken the lighting cables and/or the auxiliary metal towers will affect the directional accuracy of the aerial system by introducing unwanted signal components therein or by partly shielding it or by similar effects.

The present invention, although not limited to this application, may very advantageously be employed in connection with the energization of navigation and similar lights required to be provided adjacent aerial systems erected in or near aerodromes.

The principal object of the present invention is to provide an economical and simple arrangement whereby electrical power supply of ordinary mains (i. e. comparatively low alternating current frequency or direct current) may be taken to loads such as lamps arranged adjacent aerial systems required to have directional qualities substantially without affecting those directional qualities.

According to this invention electrical power supply to a load arranged adjacent an aerial system is effected either by utilizing a part of the aerial system itself or the lead thereto for the power supply and providing chokes for eliminating radio frequency from the power source and condensers for eliminating power from the aerial system or alternatively by arranging the power supply leads symmetrically with respect to the wires of the aerial system or part thereof.

The invention is illustrated in the accompanying diagrammatic drawing.

Referring first to Figure 1 which shows one way of carrying out the present invention as applied to the energization of navigation lamps at the head of masts carrying an aerial system, a pair of wires 1 and 2, or 3 and 4, lead down each mast (the masts are not shown) said wires serving both as the whole or part of the aerial system and as part of the lighting circuit. The wires 1 and 2, or 3 and 4, of each pair are connected together at the top of their mast through a navigation lamp 12 or 13 while the lower ends of said wires are connected through radio frequency chokes 5 and 6, or 7 and 8 and a switch 14 to the lighting mains LM. The individual wires 1 and 2, or 3 and 4, are also connected together as shown at points just above the chokes, the junction points being connected via blocking condensers 9 or 10 to a conductor 15 which is coupled at 16 to the transmitter and/or receiver (not shown) associated with the aerial system. Where the present invention is applied to aerial systems as described in British Patents 354,322 and 359,562 (an advantageous application of the present invention and the one illustrated) the conductor 15 constitutes one of the horizontal screened conductors described in said specifications while the wires of each pair of two vertical wires 1 and 2, or 3 and 4, serve in parallel as one of the aerials and in series as the mains circuit to the lamp. The blocking condensers may be enclosed in a screening box which is formed as an extension of the screen 11 for the horizontal wire 15 and this screening box may also house as much of the leads to the points above the chokes as is practicable.

In a modification illustrated in Figure 2 each lamp 12 or 13 is energized through a twin cable 17 or 18 the twin wires of which are contained within an external metal braiding or covering 19 or 20. In this arrangement the twin wires serve as the power energization circuit to the lamp 12 or 13 and the metal braiding is utilized as the aerial or part thereof, e. g. as one of the vertical aerials in a system in accordance with either of the prior specifications above referred to.

In a further modification of the last mentioned arrangement a copper tube is employed as the aerial or part thereof and the lighting cables are run inside this tube, while in yet another arrangement the aerial or part thereof is constituted by a cage of wires, e. g. four wires, within which the lighting leads are axially and symmetrically suspended.

What I claim is:

1. The combination with an antenna system having two vertical radiating aerials spaced apart and a screened horizontal feeder connected to high frequency apparatus extending between said two aerials and coupled thereto, of an electrical power supply circuit coupled to both said aerials, utilization circuits for said power circuit connected to said aerials comprising lamps, one of which is individual to each aerial, said aerials constituting power supply leads for said lamps, choke coils between said power circuit and said aerials and located at the junction thereof for preventing the flow of high frequency currents in said power circuit, and condensers between said feeder and said power circuit for preventing the flow of energy from said power circuit to said high frequency apparatus, whereby the directional qualities of said aerials are unaffected by said low frequency circuit.
2. The combination with an antenna system having two vertical radiating aerials spaced apart and a screened horizontal feeder connected to high frequency apparatus extending between said two aerials and coupled thereto, of a low frequency power supply circuit coupled to said aerials, lamps for said power circuits connected to said aerials at their upper ends, choke coils between said power circuit and said aerials and located at the lower ends of said aerials for preventing the flow of high frequency currents in said low frequency circuit, condensers between said feeder and said low frequency circuit for preventing the flow of low frequency energy from said power circuit to the high frequency apparatus, whereby the directional qualities of said aerials are unaffected by said low frequency circuit.
3. The combination with an antenna system having two pairs of vertical aerials spaced apart and a screened horizontal feeder connected to high frequency apparatus extending between said two pairs of aerials and coupled thereto, of a low frequency electrical power supply circuit coupled to both pairs of aerials, an indicator across and connecting together each pair of aerials at the uppermost portion of said aerials for preventing the flow of high frequency currents in said low frequency circuit.

quency circuit, and means for preventing the flow of low frequency energy to the high frequency apparatus, said pairs of aerials constituting power supply leads for energizing said indicators, whereby the directional qualities of said aerials are unaffected by said low frequency circuit.

4. In combination, an antenna system comprising two vertical aerials spaced apart from each other, each aerial comprising two vertical, parallel wires, a screened horizontal feeder coupled to high frequency apparatus extending between said two aerials, the two wires of each aerial being connected together at their lower ends through two condensers, and a connection including a blocking condenser between the junction point of said first two condensers and the horizontal feeder, whereby the wires of each aerial are in parallel relation with respect to the high frequency apparatus, a lamp across the upper ends of the wires of each aerial connecting said wires together, low frequency apparatus and a horizontal two-wire transmission line from said low frequency apparatus to the wires of each aerial, and a choke coil between the lower end of each wire of each aerial and said transmission line, whereby the high frequency currents from said high frequency apparatus are prevented from entering said transmission line and the directional qualities of said aerials are unaffected by said low frequency circuit.

5. The combination with an antenna system having two pairs of vertical aerials spaced apart and a screened horizontal feeder connected to high frequency apparatus extending between said two pairs of aerials and coupled thereto, of a low frequency electrical power supply circuit coupled to both pairs of aerials, an indicator across each pair of aerials at the uppermost portion thereof, and means at the lowermost portion of said aerials for preventing the flow of high frequency currents in said low frequency circuit, said pairs of aerials constituting power supply leads for energizing said indicators, whereby the directional qualities of said aerials are unaffected by said low frequency circuit.
